UNITED STATES PATENT OFFICE.

JOSEPH A. GANAHL, OF LOS ANGELES, CALIFORNIA.

WEIGHTLESS WINDOW-SASH SUPPORT.

Application filed September 30, 1924. Serial No. 740,762.

To all whom it may concern:

Be it known that I, JOSEPH A. GANAHL, a citizen of the United States, residing at Los Angeles, in the county of Los Angeles, State of California, have invented a new and useful Weightless Window-Sash Support, of which the following is a specification.

This invention relates to weightless window sash supports such as are used as attachments to the sash to support it at any height to which it may be raised in the casement, and which operate to support the sash without the use of counter-weights. The device involves the use of a roller which is resiliently pressed against the window casement and this roller is mounted in a guide which converges toward the face of the casement in an upward direction. In raising the sash the roller rolls freely on the casement, but when the sash is permitted to descend slightly the roller should jam on the casement and prevent further descent of the sash. However, in devices of this kind it is found that there is difficulty in effecting an upward movement of the roller in the guide. The general object of this invention is to provide a device of this kind with improved means for insuring a relative upward movement of the roller in the guide which will insure that the roller will press on the face of the casement with sufficient force to hold the sash in its raised position.

Further objects of the invention will appear hereinafter.

The invention consists in the novel parts and combinations of parts to be described hereinafter, all of which contribute to produce an efficient weightless window sash support.

A preferred embodiment of the invention is described in the following specification, while the broad scope of the invention is pointed out in the appended claims.

In the drawings:

Fig. 1 is a front elevation of a window with a part of its casement broken away and illustrating the point of attachment of my device.

Fig. 2 is a vertical section showing a portion of a casement with the adjacent portion of the stile of the sash, the stile being partially broken away to illustrate my device as applied to the sash.

Fig. 3 is an elevation showing a portion of the edge of a window sash with my device in position.

Fig. 4 is a section taken through the end of a bar or spring having my improvement and illustrating the parts upon an enlarged scale, to show the mode of operation of the device when in use.

Fig. 5 is a vertical section taken through a stile and illustrating another embodiment of my invention in which a single roller is employed instead of a roller on each end of a bar as shown in Fig. 2.

In Fig. 1 my device is illustrated in dotted lines applied to the stile 2 of the lower sash 3 of a window, the sash being mounted to slide vertically in the usual manner in a window casement 4.

My invention may be embodied in different types of sash supports; Figs. 2 to 4 illustrate the details of the type shown in Fig. 1, involving the use of a resilient bar or spring carrying two rollers, while Fig. 5 illustrates an embodiment of the invention involving the use of a single roller.

The embodiment illustrated in Figs. 1 to 4 includes a base-plate 5, in the form of an elongated plate secured in the bottom of a recess 6, formed in the stile 2. I provide a resilient bar or spring 7 and a bolt 8, which may be of "carriage bolt" type, which passes through the base-plate and the bar and secures the same in the stile, the outer end of the said bolt 8 being threaded and receiving a threaded sleeve 9 with an enlarged screw-head 10. A head upon this sleeve 9 seats against an annular washer 11, which receives the thrust of the sleeve when the same is tightened up on the threads of the bolt. This screw-head 10 is exposed on the face of the stile which receives the pane of glass 12 so that it can be tightened up without removing the sash. The middle portion of the bar 7 does not rest against the plate 5 but the bar does rest against the plate toward its ends for which purpose the base-plate 5 is provided with abutments 13 which may be formed by bending the plate outwardly at its ends. These abutments operate as fulcrums for the spring bar and when the sleeve 9 is tightened up the outer ends of the bar will be adjusted nearer to the inner face 14 of the casement along which the rollers 15 run. These rollers 15 are mounted in roller-carriers 16 formed on, or attached to, the ends of the bar. Each roller has a limited vertical movement in its carrier and the carrier is provided with guiding means for guiding the roller toward the casement.

100

in an upward direction; in other words, the guiding means converges toward the face 14 of the casement in an upward direction. In the present instance each roller-carrier is formed with side plates 17 and these side plates have aligning slots 18 which receive a pin 19 which extends through the roller 15 with its ends projecting into the slots. The slots in the lower roller-carrier also converge toward the face 14 in an upward direction. If desired they may be made substantially parallel with the slots in the upper roller-carrier. The guiding means for the rollers are constructed so as to permit a certain amount of play or lost motion in a lateral direction. In the construction illustrated this is accomplished by having the pins of the rollers considerably smaller than the width of the slots.

Associated with the roller-carrier I provide means for facilitating a relative upward movement of the roller in the guiding means which operates when the sash has been raised and then permitted to descend a slight distance. For this purpose I provide the roller-carrier with means for engaging the side of the roller which is opposite to the side of the roller which is opposite to the casement face 14, and this may be in the form of a projecting nose 20; in the present instance this is in the form of a convex plate located at the side of the guiding means which is opposite to the window casement, and, if desired, it may be scored or formed with serrations 21 on its convex face. If desired, this nose may be struck up from the material of the roller carrier, see Fig. 5.

In considering the mode of operation of the device it should be understood that it is not the friction developed at the rollers or their pins that directly supports the device, but it is the pressure of the opposite stile against the face of the casement, that supports the sash. When the sash has been raised to the desired height, if it is permitted to descend slightly, the sash will have a relative downward movement with respect to the rollers, and this movement will be sufficient to cause an engagement of the faces of the noses 20 with the rollers. This will cause the rollers to roll upwardly on the noses and transfers the pins of the rollers to the upper ends of the guide slots. The slots are widened out as may be necessary to clear the pin when the roller is moved laterally in the slot in effecting this upward movement. When the rollers are located at the upper ends of the guide slots, the pressure of the sash laterally against the casement will operate to support the sash in its raised position. In lowering the sash it may be pushed down by exerting sufficient force, but this downward movement of the sash will not cause any change in the position of the rollers at the upper ends of the slots. This mode of operation is illustrated in Fig. 4.

Instead of embodying my invention in this bar type of sash support, I may embody it in a type of sash support in which a single roller 22 is provided (see Fig. 5). In this case the roller-carrier 23 is in the form of an open box with end walls 24 which are guided in a box-formed guide 25 which is counter-sunk in a recess 26 in the inner face 27 of the stile 28. The roller-carrier has side walls 29 provided with guiding means, such as slots 30, which converge toward the face of the window casement in an upward direction. In this instance the engaging means for the face of the roller 22 which is remote from the casement is in the form of a plate 31 struck from the box wall, and carrying the stem 32; the outer end of this stem is received in an inner sleeve 33 which is threaded in a bushing 34 set in the stile. A space is left between the bottom wall 35 of the carrier and the bottom wall 36 of the socket-plate or bracket 25, and in this space a coil spring 37 is provided disposed around the stem 32. This spring exerts its force to shove the carrier and roller resiliently outwardly and presses the roller 22 against the face of the casement. The bushing 34 is held in place by a ferrule 38 which is screwed on its ends which projects beyond the outer face of the stile. By applying a screw-driver in the screw-slot 39 at the outer end of the inner sleeve 33, the pressure of this spring can be adjusted, it being understood that the end of this spring thrusts against the inner end of the sleeve 33.

With this embodiment of the invention the mode of operation is substantially the same as that described above in connection with Figs. 1 to 4. In this construction also there should be some lateral or horizontal play of the roller in the guiding means. In the present instance this is accomplished as in the first embodiment of the invention described, by making the pin 40 of smaller diameter than the wide parts of the slots 30. In raising the sash the pressure of the spring is relieved because the rollers will drop down to the lower ends of the slots, so that the only resistance offered is the weight of the sash.

If desired the springs can be adjusted to such an extent that the rollers will stay at the lower ends of the slots. The sashes can then be raised or lowered by exerting more force.

In practice, the inner end of the stem 32 is slightly upset to form a knob 32^a, and the mouth of the sleeve 33 is slightly burred down as indicated to contract it slightly. This keeps the stems 32 from coming out of the sleeves in being thrown about or handled.

It is understood that the embodiment of the invention described herein is only one of the many embodiments this invention may

take, and I do not wish to be limited in the practice of the invention, nor in the claims, to the particular embodiment set forth.

What I claim is:

5. 1. In a weightless window sash support, the combination of a roller, a roller-carrier supporting the roller, with means for supporting the carrier in the stile of the sash and for pressing the roller against the side 10 of the window casement, said roller-carrier having means for guiding the roller along a line converging toward the casement in an upward direction, and a shoe associated with the roller carrier for engaging the face 15 of the roller remote from the casement and cooperating with the roller when the sash is moved downwardly to effect a relative movement of the roller upwardly in the guiding means and out of engagement with the shoe, thereby increasing the pressure on the casement to support the sash.

2. In a weightless window sash support, the combination of a roller having a pin 20 projecting at its ends, a roller-carrier having a slot at each side receiving the ends of the pin and converging toward the casement in an upward direction, said roller-carrier having means for supporting the same in the stile of the sash and for pressing the roller against the side of the window casement, and a shoe associated with the roller-carrier for engaging the face of the roller opposite to the casement and cooperating with the roller when the sash is moved 25 downwardly to effect a relative movement of the roller upwardly in the slots and out of engagement with the shoe, thereby increasing the pressure on the casement to support the sash, and means for adjusting 30 the position of the roller-carrier to regulate the pressure of the roller against the casement.

3. In a weightless window sash support, the combination of a roller, a roller-carrier 35 supporting the roller, with means for supporting the carrier in the stile of the sash and for pressing the roller against the side of the window casement, said roller-carrier having means for guiding the roller along a line converging toward the casement in an upward direction, and a shoe in the form 40 of a plate having its face disposed adjacent to the side of the roller opposite to the casement, and operating to engage the face of the roller when the sash is moved downwardly, to effect a relative movement of the roller upwardly in the guiding means and out of engagement with the plate, thereby increasing the pressure on the casement to 45 support the sash.

4. In a weightless window sash support, the combination of a bar mounted on the side of the stile of the sash, with means for resiliently pressing the same toward the 50 side of the casement, a roller, a roller-car-

rier on the bar supporting the roller and having means for guiding the roller along a line converging toward the casement in an upward direction, and a shoe having a nose 55 projecting toward the casement for engaging the face of the roller remote from the casement and cooperating with the roller when the sash is moved downwardly to effect a relative movement of the roller upwardly in the guiding means and out of engagement with the shoe, thereby increasing the pressure on the casement to support the sash.

5. In a weightless window sash support, the combination of a resilient bar with means 60 for mounting the same in the stile of a window sash, a roller at each end of the bar, a roller carrier corresponding to each roller at each end of the bar and having means for guiding each roller along a line 65 converging toward the casement in an upward direction, and engaging means associated with the roller-carrier for engaging the face of each roller on its side opposite to the casement and cooperating with the 70 rollers when the sash is moved downwardly to effect a relative movement of the roller upwardly in the guiding means and out of engagement with the engaging means, thereby increasing the pressure on the casement 75 to support the sash.

6. In a weightless window sash support, the combination of a base-plate adapted to be mounted in the stile of a window sash and having an abutment disposed toward 80 each end, a resilient bar with its outer portions resting against the abutments and having means for securing its middle portion to the stile between the abutments so that the projecting outer ends of the bar are yieldingly pressed toward the casement, a roller 85 at each end of the bar, a roller-carrier corresponding to each roller carried on each end of the bar, each roller-carrier having two side plates with aligning slots converging 90 toward the casement in an upward direction and each roller having a pin guided in its slots, and a nose associated with each roller carrier projecting toward the window-casement for engaging the face of the 95 roller remote from the casement and cooperating with the roller when the sash is moved downwardly to effect a relative movement of the roller upwardly in the slots and out of engagement with the nose, thereby 100 increasing the pressure on the casement to support the sash.

7. In a weightless window sash support, the combination of a roller having a pin 105 projecting at its ends, a roller-carrier having a slot at each side of considerably larger width than the pin so as to permit lateral movement of the pin in the slots, said slots receiving the ends of the pin and converging 110 toward the casement in an upward direction.

tion, said roller-carrier having means for supporting the same in the stile of the sash and for pressing the roller against the side of the window casement, and a shoe associated with the roller-carrier, located at the side of the guiding means, for engaging the face of the roller remote from the casement and cooperating with the roller when the

sash is moved downwardly to effect a relative movement of the roller upwardly in 10 the slots and out of engagement with the shoe, thereby increasing the pressure on the casement to support the sash.

Signed at Los Angeles, California, this 23d day of September, 1924.

JOSEPH A. GANAHL.
